(57) **ABSTRACT**

Piezoelectric compounds of the formula $xNa_mBi_nTiO_3-yK_mBi_nTiO_3-zLi_mBi_nTiO_3-pBaTiO_3$ where $(0 < x \leq 1)$, $(0 \leq y \leq 1)$, $(0 \leq z \leq 1)$, $(0.3 \leq m \leq 0.7)$, $(0.3 \leq n \leq 0.7)$, $(0 < p \leq 1)$ ($0.9 \leq m/n \leq 1.1$) as well as to doped variations thereof are disclosed. The material is suitable for high power applications.

NBT BASED LEAD-FREE PIEZOELECTRIC MATERIALS FOR HIGH POWER APPLICATIONS

Matter enclosed in heavy brackets [ ] appears in the original patent but forms no part of this reissue specification; matter printed in italics indicates the additions made by reissue; a claim printed with strikethrough indicates that the claim was canceled, disclaimed, or held invalid by a prior post-patent action or proceeding.

This application claims priority to U.S. provisional patent application 61/194,461 filed Sep. 26, 2008.

FIELD OF THE INVENTION

The disclosed invention relates to hard lead free piezoelectric materials.

BACKGROUND OF THE INVENTION

Hard PZT ferroelectric materials such as PZT4 and PZT8 have been the mainstay in last half century for high power applications. However, the lead content in PZT type ceramics is an environmental concern in electronic devices. For example, the European Union is proposing directives on waste from electrical and electronic equipment as well restrictions on hazardous substances and end-of life vehicles. The USA and Japan are expected to issue similar environmental regulations. It therefore is desirable to develop lead-free piezoelectric ceramics to replace lead-based materials.

Lead-free ceramic compounds may be categorized into three primary types, all of which have the ABO_3 perovskite formulation: (1) $BaTiO_3$ ("BT"), (2) $K_{0.5}Na_{0.5}NbO_3$ ("KNN") and (3) $Na_{0.5}Bi_{0.5}TiO_3$ ("NBT"). These compounds, however, either display low T_c ($\leq 120^\circ C$), show low piezoelectric activity, multiple polymorphic phase transitions as well as depolarization temperature which limit their utility. Various properties of these compounds are shown in Table I. In Table I, KCN is $K_4CuNb_8O_{23}$ and MPB is Morphotropic Phase Boundary.

Lead-free ceramic compounds such as solid solutions of NBT with $K_{0.5}Bi_{0.5}TiO_3$ ("KBT"), NBT-KBT-BT, NBT-KBT- with $Li_{0.5}Bi_{0.5}TiO_3$ ("LBT") show a morphotropic phase boundary analogous to PZT and relaxor-PT systems. 5 NBT-KBT, NBT-KBT-BT, and NBT-KBT-LBT, however, exhibit a nonpolar antiferroelectric phase transition temperature that occurs below their T_c that limits their temperature range of use. Lead-free ceramic compounds such as KNN— $LiNbO_3$ ("KNN-LN"), KNN— $LiTaO_3$ ("KNN-LT"), 10 KNN— $LiSbO_3$ ("KNN-LS"), and KNN— $Sr(Ba)TiO_3$ have piezoelectric properties comparable to hard PZT ceramic compounds. However, these KNN type lead-free compounds exhibit low mechanical quality factor Q and a shift 15 in the orthorhombic-tetragonal polymorphic phase transition temperature from about $200^\circ C$. to about room temperature. This polymorphic phase transition significantly limits their utility due to property variations.

A need therefore exists for high performance lead free 20 piezoelectric ceramic materials that avoid the toxic lead of prior art $Pb(Zr_xTi_{1-x})O_3$ ("PZT") piezoelectric ceramics and the disadvantages of prior art, lead free piezoelectric ceramics.

BRIEF DESCRIPTION OF THE DRAWINGS

FIG. 1 shows a compositional diagram of NBT-based compositions;

FIG. 2 (a) shows piezoelectric coefficient (d_{33}) and 30 mechanical quality factor (Q_m) as a function of Mn level in BNBK 79 piezoelectric compounds;

FIG. 2(b) shows dielectric permittivity (K) and dielectric loss ($\tan \delta$) as a function of Mn dopant level in BNBK 79 piezoelectric compounds;

FIG. 2 (c) shows electromechanical coupling factors (k_{ij}) 35 as a function of Mn dopant level in BNBK79 piezoelectric compounds;

FIG. 3 shows polarization hysteresis for BNBK 79-0.8 wt % MnO_2 piezoelectric compound of example 1G compared 40 to PZT4 and PZT8;

FIG. 4 shows strain hysteresis of lead free BNBK 79 of example 1A and 0.8 wt % MnO_2 doped BNBK 79 of example 1G piezoelectric compounds compared to PZT4 and PZT8;

FIG. 5(a) shows dielectric permittivity and dielectric loss as a function of temperature for undoped BNBK 79 piezoelectric compounds at 1 kHz, 10 kHz and 100 kHz;

FIG. 5(b) shows dielectric permittivity and dielectric loss for 0.5 wt % MnO_2 doped BNBK 79 piezoelectric compounds at 1 kHz, 10 kHz and 100 kHz;

FIG. 5(c) shows dielectric permittivity and dielectric loss for 0.8 wt % MnO_2 doped BNBK 79 piezoelectric compounds at 1 kHz, 10 kHz and 100 kHz;

FIG. 5(d) shows dielectric permittivity and dielectric loss for 1.0 wt % MnO_2 doped BNBK 79 piezoelectric compounds at 1 kHz, 10 kHz and 100 kHz;

FIG. 6 shows electromechanical coupling factors in extensional mode and thickness mode for 0.8 wt % MnO_2 doped BNBK 79 of Example 1G piezoelectric compounds;

FIG. 7 shows variation of planar electromechanical coupling factor as a function of temperature for BNBK 79-0.8 wt % MnO_2 piezoelectric compounds compared to PZT4 and PZT8.

FIGS. 8(a)-8(c) show temperature dependence of dielectric behavior for Co_2O_3 doped vacancy defect engineered BNKLBT ceramics.

FIG. 9 shows temperature dependence of electromechanical coupling factor, including thickness coupling k_t and planar coupling k_p , for Co_2O_3 doped vacancy defect engineered BNKLBT ceramics, exhibiting a very stable temperature behavior till their depolarization temperature T_d .

FIG. 10 shows the temperature dependence of mechanical quality factor Q , for Co_2O_3 doped vacancy defect engineered BNKLBT ceramics, where the Q values are larger than 700 at room temperature, gradually decreased with increasing temperature, keep yet high Q value around 200 when the temperature approaching the depolarization temperature T_d .

SUMMARY OF THE INVENTION

The NBT-based piezoelectric materials disclosed herein typically possess high internal bias field of more than about 5 kV/cm and high mechanical quality factor of more than about 700, comparable to PZT4 and PZT8. The NBT based materials of the general formula $x\text{Na}_m\text{Bi}_n\text{TiO}_3\text{-yK}_m\text{Bi}_n\text{-TiO}_3\text{-zLi}_m\text{Bi}_n\text{TiO}_3\text{-pBaTiO}_3$ where $(0 < x \leq 1)$, preferably $(0.3 \leq x \leq 0.95)$, more preferably $(0.3 \leq x \leq 0.8)$, $(0 \leq y \leq 1)$, preferably $(0 \leq y \leq 0.7)$, more preferably $(0 \leq y \leq 0.2)$, $(0 \leq z \leq 1)$, preferably $(0 \leq z \leq 0.5)$, more preferably $(0 \leq z \leq 0.2)$; $(0.3 \leq m \leq 0.7)$, preferably $(0.4 \leq m \leq 0.6)$, more preferably $(0.45 \leq m \leq 0.55)$; $(0.3 \leq n \leq 0.7)$, preferably $(0.4 \leq n \leq 0.6)$, more preferably $(0.45 \leq n \leq 0.55)$ such as $n=0.495$; $(0 < p < 1)$, preferably $(0 < p \leq 0.2)$, more preferably $(0 < p \leq 0.1)$; $(x+y+z+p=1)$, $(0.9 \leq m+n \leq 1.1)$ and $(0.9 \leq m/n \leq 1.1)$, may be modified with various acceptor dopants (single dopant, multiple dopant) to have a wide temperature usage range of from about -50°C . to about 200°C . The low densities of NBT-based piezoelectric compounds, on the order of about 5.8 g/cc vs. about 7.6 g/cc for PZT piezoelectric compounds, enable the NBT-based piezoelectric compounds to achieve high acoustic velocities.

The NBT-based piezoelectric compounds possess improved "hardening" effect compared to conventional hard PZT piezoelectric compounds and may be used to replace lead containing piezoelectric materials such as PZT4 and PZT 8.

The NBT-based piezoelectric compounds are environmentally friendly materials that may be used in high power electronic devices such as high power ultrasonic transducers

(probes), ultrasonic motors, piezoelectric transformers and high intensity focused ultrasound transducers.

DETAILED DESCRIPTION OF THE INVENTION

In a first aspect, undoped compounds within the region bounded by $y \leq 50\%$, $z \leq 20\%$ shown in FIG. 1 may be produced. These compounds are within the general formula (I) $x\text{Na}_m\text{Bi}_n\text{TiO}_3\text{-yK}_m\text{Bi}_n\text{TiO}_3\text{-zLi}_m\text{Bi}_n\text{TiO}_3\text{-pBaTiO}_3$ where $(0 < x \leq 1)$, preferably $(0.3 \leq x \leq 0.95)$, more preferably $(0.3 \leq x \leq 0.8)$; $(0 \leq y \leq 1)$, preferably $(0 \leq y \leq 0.7)$, more preferably $(0 \leq y \leq 0.2)$ and $(0 \leq z \leq 1)$, preferably $(0 \leq z \leq 0.5)$, more preferably $(0 < z \leq 0.2)$; $(0.3 \leq m \leq 0.7)$, preferably $(0.4 \leq m \leq 0.6)$, more preferably $(0.45 \leq m \leq 0.55)$; $(0.3 \leq n \leq 0.7)$, preferably $(0.4 \leq n \leq 0.6)$, more preferably $(0.45 \leq n \leq 0.55)$; $(0 < p < 1)$, preferably $(0 < p \leq 0.2)$, more preferably $(0 < p \leq 0.1)$, $(x+y+z+p=1)$ and $(0.9 \leq m/n \leq 1.1)$.

Starting materials which may be used include but are not limited to K_2CO_3 (99.9% pure from Alfa Aesar), Na_2CO_3 (99.9% pure from Alfa Aesar), Li_2CO_3 (99.9% pure from Alfa Aesar), BaCO_3 (99.9% pure from Alfa Aesar), Bi_2O_3 (99.99% pure from MCP) and TiO_2 (99.99% pure from Ishihara). Dopant sources which may be employed include but are not limited to Al_2O_3 , CoO , Co_2O_3 , Re_2O_3 (where Re is rare earth element), NiCO_3 , MnO_2 , MnCO_3 , Fe_2O_3 , and mixtures thereof. The dopants have a purity of 99.99% or more and are commercially available from sources such as Alfa Aesar.

Manufacture of piezoelectric compounds within general formula (I) entails use of starting materials such as those above that are dried at about 120°C . in air for about 10 hrs to about 20 hrs to remove moisture.

The dried starting materials are blended into a mixture for use in manufacture of undoped BNBK type compound such as $x\text{Na}_{0.5}\text{Bi}_{0.5}\text{TiO}_3\text{-yK}_{0.5}\text{Bi}_{0.5}\text{TiO}_3\text{-zBaTiO}_3$. The mixture then is calcined in an oxidizing atmosphere such as air at about 700°C . to about 950°C ., preferably about 800°C . to 900°C ., more preferably about 850°C . to about 880°C . for about 0.5 hr to about 5 hrs, preferably about 1 hr to about 3 hrs, more preferably about 2 hrs to yield a calcined mixture. The calcined mixture then is vibration milled in a lower alkanol such as anhydrous ethanol to produce a milled material that has a particle size of about 0.5 micron to about 3 microns preferably about 1 micron to about 2 microns, more preferably about 1 micron.

The milled material is optionally mixed with up to about 2 wt % of an optional organic binder based on the weight of milled material to produce a milled material composition. Useful binders include but are not limited to polyvinyl alcohol, polyvinyl butyral, and aqueous acrylic polymer emulsions such as Rhoplex from Rohm & Haas, polyethyleneimine and mixtures thereof. The milled material, optionally with binder composition is compressed at about 3000 PSI to about 10000 PSI, preferably about 5000 PSI to about 8000 PSI, more preferably about 5000 PSI to about 6000 PSI to yield a preform.

The preform is heated to about 500°C . to about 600°C ., preferably about 350°C . to about 550°C ., more preferably about 500°C . to about 550°C . to remove binder that may be present and to yield a green preform. The green preform then is sintered at about 1000°C . to about 1250°C ., such as about 1060°C . to about 1220°C ., preferably about 1050°C . to about 1150°C ., more preferably about 1100°C . for about 0.5 hr to about 5 hrs, preferably about 1 hr to about 2 hrs, more preferably about 2 hrs to yield a sintered product.

The density of the sintered product typically is about 5.0 g/cm³ to about 5.7 g/cm³, preferably about 5.7 g/cm³ which represents $\geq 95\%$ of the theoretical density. The sintered products typically have a perovskite type crystal structure.

The sintered products are polished to a thickness of about 0.5 mm. The resulting polished products are electroded with fire-on-silver paste such as DuPont 6160 to produce an electroded sample. The electroded samples are poled at about 20° C. to about 120° C., preferably about 20° C. to about 50° C., more preferably about 25° C. (room temperature) with an electric field of about 30 kV/cm to about 60 kV/cm, preferably about 40 kV/cm to about 50 kV/cm, more preferably about 40 kV/cm for about 3 min to about 30 min, preferably about 5 min to about 10 min, more preferably about 10 min.

In a second aspect, doped piezoelectric compounds of the general formula (IA),

where (0 < x ≤ 1), preferably (0.3 ≤ x ≤ 0.95), more preferably (0.3 ≤ x ≤ 0.8); (0 ≤ y ≤ 1), preferably (0 ≤ y ≤ 0.7), more preferably (0 ≤ y ≤ 0.2), (0 ≤ z ≤ 1), preferably (0 ≤ z ≤ 0.5), more preferably (0 ≤ z ≤ 0.2); (0 < p < 1), preferably (0 < p ≤ 0.2), more preferably (0 < p ≤ 0.1); (x+y+z+p=1); 0.3 ≤ m ≤ 0.7, preferably 0.4 ≤ m ≤ 0.6, more preferably 0.45 ≤ m ≤ 0.55; 0.3 ≤ n ≤ 0.7, preferably 0.4 ≤ n ≤ 0.6, more preferably 0.45 ≤ n ≤ 0.55; and 0.9 ≤ m/n ≤ 1.1, preferably 0.95 ≤ m/n ≤ 1.05, more preferably 0.98 ≤ m/n ≤ 1.02 and (0 wt % < r ≤ 5 wt %), preferably 0.2 wt % ≤ r ≤ 2 wt %, more preferably 0.5 wt % ≤ r ≤ 1 wt %, where r is based on the weight of a compound within the scope of xNa_mBi_nTiO₃-yK_mBi_nTiO₃-zLi_mBi_nTiO₃-pBaTiO₃ where x, y, z, m, n and p are defined as above, and M is a dopant such as Al₂O₃, CoO, Re₂O₃ where Re is a rare earth element, NiO, MnO₂, Fe₂O₃, and mixtures thereof may be produced.

In this second aspect, the starting materials are dried and then blended into a mixture for use in manufacture of undoped compound within the scope of general formula (I). The mixture then is calcined in an oxidizing atmosphere such as air at about 700° C. to about 950° C., preferably about 800° C. to about 900° C., more preferably about 850° C. to about 880° C. for about 0.5 hr to about 5 hrs, preferably about 1 hr to about 3 hrs, more preferably about 2 hrs to yield a calcined mixture. The calcined mixture then is blended with a dopant to provide a doped mixture suitable for manufacture of a compound with the general formula (IIA) that is vibration milled in a lower alkanol such as anhydrous ethanol to produce a milled material that has a particle size of about 0.5 micron to about 3 microns, preferably about 1 micron to about 2 microns, more preferably about 1 micron.

The milled material optionally may be mixed with an optional organic binder in an amount of up to about 2 wt. %, based on the weight of milled material to produce a milled material composition. Useful binders include but are not limited to polyvinyl alcohol, polyvinyl butyral, aqueous acrylic polymer emulsions such as Rhoplex from Rohm & Haas, polyethyleneimine and mixtures thereof.

The milled material composition is compressed at about 3000 PSI to about 10000 PSI, preferably about 5000 PSI to about 8000 PSI, more preferably about 5000 PSI to about 6000 PSI to yield a preform. The preform then is heated to about 500° C. to about 600° C., preferably about 350° C. to about 550° C., more preferably about 550° C. to remove binder that may be present and to yield a green preform. The green preform is sintered at about 1000° C. to about 1250° C., preferably about 1050° C. to about 1150° C., more

preferably about 1100° C. for about 0.5 hr to about 5 hrs, preferably about 1 hr to about 2 hrs, more preferably about 2 hrs to yield a sintered product.

The sintered products are polished and electroded with fire-on-silver paste such as DuPont 6160 to produce electroded samples. The electroded samples are poled at about 20° C. to about 120° C., preferably about 20° C. to about 50° C., more preferably about 25° C. (room temperature) with an electric field of about 30 kV/cm to about 60 kV/cm, preferably about 40 kV/cm to about 50 kV/cm, more preferably about 40 kV/cm for about 3 min to about 30 min, preferably about 5 min to about 10 min, more preferably 10 min.

In a third aspect, compounds of the general formula (II)

such as xNa_{0.5}Bi_{0.5}TiO₃-yK_{0.5}Bi_{0.5}TiO₃-zLi_{0.5}Ba_{0.5}TiO₃ where (0 < x ≤ 1), preferably (0.3 ≤ x ≤ 0.95), more preferably (0.30 ≤ x ≤ 0.8); (0 < y ≤ 1), preferably (0 < y ≤ 0.7), more preferably (0 < y ≤ 0.5), (0 < z ≤ 1), preferably (0 < z ≤ 0.5), more preferably (0 < z ≤ 0.2) (x+y+z=1); 0.3 ≤ m ≤ 0.7, preferably 0.4 ≤ m ≤ 0.6, more preferably 0.45 ≤ m ≤ 0.55; 0.3 ≤ n ≤ 0.7, preferably 0.4 ≤ n ≤ 0.6, more preferably 0.45 ≤ n ≤ 0.55; 0.9 ≤ m+n < 1.1 and 0.9 ≤ m/n ≤ 1.1, preferably 0.95 ≤ m/n ≤ 1.05, more preferably 0.98 ≤ m/n ≤ 1.02 may be produced.

In this third aspect, dried starting materials such as K₂CO₃, Na₂CO₃, TiO₂, Bi₂O₃, BaCO₃ and Li₂CO₃ are blended into a mixture for use in manufacture of undoped piezoelectric compound within general formula (II). The mixture then is calcined in air at about 700° C. to about 950° C., preferably about 800° C. to about 900° C., more preferably about 850° C. to about 880° C. for about 0.5 hr to about 3 hrs, preferably about 1 hr to about 2 hrs to yield a calcined mixture.

The calcined mixture then is vibration milled in a lower alcohol such as anhydrous ethanol to produce a milled material that has a particle size of about 0.5 micron to about 3 microns, preferably about 1 micron to about 2 microns, more preferably about 1 micron. The milled material then is optionally mixed with up to about 2 wt. % of an organic binder based on the weight of milled material to produce a milled material composition. Useful binders include but are not limited to polyvinyl alcohol, polyvinyl butyral, aqueous acrylic polymer emulsions such as Rhoplex from Rohm & Haas, polyethyleneimine and mixtures thereof.

The milled material composition, optionally with binder, is compressed at about 3000 PSI to about 8000 PSI preferably about 5000 PSI to about 8000 PSI, more preferably about 5000 PSI to about 6000 PSI to yield a preform. The preform then is heated to about 500° C. to about 550° C., preferably about 550° C. to remove binder that may be present and to yield a green preform. The green preform then is sintered at about 1000° C. to about 1250° C., preferably about 1050° C. to about 1150° C., more preferably about 1100° C. for about 0.5 hrs to about 5 hrs, preferably about 1 hrs to about 2 hrs, more preferably about 2 hrs to yield a sintered product.

The sintered products are polished and electroded with fire-on-silver paste such as DuPont 6160 to produce electroded samples. The electroded samples are poled at about 20° C. to about 120° C., preferably about 20° C. to about 50° C., more preferably about 25° C. with an electric field of about 20 kV/cm to about 60 kV/cm, preferably about 40 kV/cm to about 50 kV/cm, more preferably about 40 kV/cm for about 3 min to about 30 minutes, preferably about 5 min to about 10 min, more preferably about 10 min.

In a fourth aspect, doped compounds within the general formula (IIA)

where $(0 < x \leq 1)$, preferably $(0.3 \leq x \leq 0.9)$, more preferably $(0.30 \leq x \leq 0.8)$; $(0 < y \leq 1)$, preferably $(0 < y \leq 0.7)$, more preferably $(0 < y \leq 0.2)$, $(0 < z \leq 1)$, preferably $(0 < z \leq 0.5)$, more preferably $(0 < z \leq 0.2)$; $(x+y+z=1)$, $0.3 \leq m \leq 0.7$, preferably $0.4 \leq m \leq 0.6$, more preferably $0.45 \leq m \leq 0.55$, $0.3 \leq n \leq 0.7$, preferably $0.4 \leq n \leq 0.6$, more preferably $0.45 \leq n \leq 0.55$; $0.9 \leq m+n \leq 1.1$, preferably $0.95 \leq m+n \leq 1.05$, more preferably $0.98 \leq m+n \leq 1.02$ and N is a dopant such as Al_2O_3 , CoO , Re_2O_3 where Re is a rare earth element, NiO , MnO_2 , Fe_2O_3 , and mixtures thereof may be produced and $(0 < v \leq 5$ wt %) preferably 0.2 wt % $\leq v \leq 2$ wt %, more preferably 0.5 wt % $\leq v \leq 1$ wt %, where v is based on the weight of a compound within the scope of the formula $xNa_mBi_nTiO_3-yK_mBi_nTiO_3-zLi_mBa_nTiO_3$ where x, y, z, m and n are defined as above.

In this fourth aspect, starting materials are dried and then blended into a mixture for use in manufacture of undoped compounds within the scope of general formula (II). The mixture then is calcined in air at about $700^\circ C$. to about $950^\circ C$., preferably about $800^\circ C$. to about $900^\circ C$., more preferably about $850^\circ C$. to about $880^\circ C$. for about 0.5 hrs to about 3 hrs, preferably about 1 hr to about 2 hrs, more preferably about 2 hrs to yield a calcined mixture. The calcined mixture then is blended with a dopant to provide a doped mixture that is vibration milled in a lower alkanol such as anhydrous ethanol to produce a milled material that has a particle size of about 0.5 micron to about 3 microns, preferably about 1 micron to about 2 microns, more preferably about 1 micron.

The milled material optionally may be mixed with up to about 2 wt. % of an organic binder, based on the weight of milled material to produce a milled material composition. Useful binders include but are not limited to polyvinyl alcohol, polyvinyl butyral, aqueous acrylic polymer emulsions such as Rhoplex from Rohm & Haas, polyethyleneimine and mixtures thereof.

The milled material composition is compressed at about 3000 PSI to about 10000 PSI, preferably about 5000 PSI to about 8000 PSI, more preferably about 5000 PSI to about 6000 PSI to yield a preform. The preform then is heated to about $500^\circ C$. to about $700^\circ C$., preferably about $550^\circ C$. to remove any binder present to yield a green preform. The green preform then is sintered at about $1000^\circ C$. to about $1250^\circ C$., preferably about $1050^\circ C$. to about $1150^\circ C$., more preferably about $1100^\circ C$. for about 0.5 hr to about 5 hrs, preferably about 1 hr to about 2 hrs, more preferably about 2 hrs to yield a sintered product.

The sintered products are polished and electrode with fire-on-silver paste such a DuPont 6160 to produce an electrode sample. The electrode samples are poled at about $20^\circ C$. to about $120^\circ C$., preferably $20^\circ C$. to about $50^\circ C$., more preferably about $25^\circ C$. with an electric field of about 30 kV/cm to about 60 kV/cm, preferably about 40 kV/cm to about 50 kV/cm, more preferably about 40 kV/cm to about 50 kV/cm, more preferably about 40 kV/cm for about 3 min to about 30 min, preferably about 5 min to about 10 min, more preferably 10 min.

In a fifth aspect, compounds of the general formula (III)

where $(0 < x \leq 1)$, preferably $(0.3 \leq x \leq 0.95)$, more preferably $(0.3 \leq x \leq 0.8)$; $(0 < y \leq 1)$, preferably $(0 < y \leq 0.7)$, more preferably $(0 < y \leq 0.2)$ and $(0 < z \leq 1)$, preferably $(0 < z \leq 0.5)$, more preferably $(0 < z \leq 0.2)$; $(x+y+z=1)$, $0.3 \leq m \leq 0.7$, preferably

$0.4 \leq m \leq 0.6$, more preferably $0.45 \leq m \leq 0.55$; $0.3 \leq n \leq 0.7$, preferably $0.4 \leq n \leq 0.6$, more preferably $0.45 \leq n \leq 0.55$; $0.9 \leq m+n \leq 1.1$, and $0.9 \leq m+n \leq 1.1$, preferably $0.95 \leq m+n \leq 1.05$, more preferably $0.98 \leq m+n \leq 1.02$ may be produced.

Dried starting materials such as Na_2CO_3 , TiO_2 , Bi_2O_3 , $BaCO_3$ and Li_2CO_3 are blended into a mixture for use in manufacture of undoped piezoelectric compounds within general formula (III) such as $xNa_{0.5}Bi_{0.5}TiO_3-yLi_{0.5}Bi_{0.5}TiO_3-zBaTiO_3$. The mixture then is calcined in air at about $700^\circ C$. to about $950^\circ C$., preferably about $800^\circ C$. to about $900^\circ C$., more preferably about $850^\circ C$. to about $880^\circ C$. for about 0.5 hr to about 2 hrs, preferably about 2 hrs yield a calcined mixture. The calcined mixture then is vibration milled in a lower alkanol such as anhydrous ethanol to produce a milled material that has a particle size of about 0.5 micron to about 3 microns, preferably about 1 micron to about 2 microns, more preferably about 2 microns. The milled material then is optionally mixed with up to about 2 wt. % of an organic binder based on the weight of milled material to produce a milled material composition. Useful binders include but are not limited to polyvinyl alcohol, polyvinyl butyral, aqueous acrylic polymer emulsions such as Rhoplex from Rohm & Haas, polyethyleneimine and mixtures thereof.

The milled material, optionally with binder, is compressed at about 3000 PSI to about 10000 PSI, preferably about 5000 PSI to about 8000 PSI, more preferably about 5000 PSI to about 6000 PSI to yield a preform. The preform then is heated to about $500^\circ C$. to about $650^\circ C$., preferably about $550^\circ C$. to remove binder that may be present and to yield a green preform. The green preform then is sintered at about $1000^\circ C$. to about $1250^\circ C$., preferably about $1050^\circ C$. to about $1150^\circ C$., more preferably about $1100^\circ C$. for about 0.5 hr to about 5 hrs, preferably about 1 hr to about 2 hrs, more preferably about 2 hrs to yield a sintered product.

The sintered products are polished and electrode with fire-on-silver paste such a DuPont 6160 to produce an electrode sample. The electrode samples are poled at about $20^\circ C$. to about $120^\circ C$., preferably about $20^\circ C$. to about $50^\circ C$., more preferably about $25^\circ C$. with an electric field of about 30 kV/cm to about 60 kV/cm, preferably about 40 kV/cm to about 50 kV/cm, more preferably about 40 kV/cm for about 3 min to about 30 min, preferably about 5 min to about 10 min, more preferably about 10 min.

In a sixth aspect, doped compounds of the general formula IIIA

where $(0 < x \leq 1)$, preferably $(0.3 \leq x \leq 0.95)$, more preferably $(0.3 \leq x \leq 0.8)$; $(0 < y \leq 1)$, preferably $(0 < y \leq 0.7)$, more preferably $(0 < y \leq 0.2)$ and $(0 < z \leq 1)$, preferably $(0 < z \leq 0.5)$, more preferably $(0 < z \leq 0.2)$, $(x+y+z=1)$; $0.3 \leq m \leq 0.7$, preferably $0.4 \leq m \leq 0.6$, more preferably $0.45 \leq m \leq 0.55$; $0.3 \leq n \leq 0.7$, preferably $0.4 \leq n \leq 0.6$, more preferably $0.45 \leq n \leq 0.55$; $0.9 \leq m+n \leq 1.1$, and $0.9 \leq m+n \leq 1.1$, preferably $0.95 \leq m+n \leq 1.05$, more preferably $0.98 \leq m+n \leq 1.02$ ($0 < w \leq 5$ wt %) preferably 0.2 wt % $\leq w \leq 2$ wt %, more preferably 0.5 wt % $\leq w \leq 1$ wt %, where w is based on the weight of a compound within the scope of the formula $xNa_mBi_nTiO_3-yLi_mBi_nTiO_3-zBaTiO_3$ where x, y, z, m and n are defined as above and where N is a dopant such as Al_2O_3 , CoO , Re_2O_3 where Re is a rare earth element, NiO , MnO_2 , Fe_2O_3 , and mixtures thereof.

In this sixth aspect, starting materials are dried and then blended into a mixture for use in manufacture of undoped piezoelectric compounds within general formula (III). The mixture then is calcined in air at about $700^\circ C$. to about $950^\circ C$., preferably about $800^\circ C$. to about $900^\circ C$., more preferably

erably about 850° C. to about 880° C. for about 0.5 hr to about 5 hrs, preferably about 1 hr to about 3 hrs, more preferably about 2 hrs to yield a calcined mixture.

The calcined mixture then is blended with a dopant to provide a doped mixture that is vibration milled in a lower alkanol such as anhydrous ethanol to produce a milled material that has a particle size of about 0.5 micron to about 3 microns, preferably about 1 micron to about 2 microns, more preferably about 2 microns.

The milled material optionally may be mixed with an organic binder in an amount of up to about 2 wt. %, based on the weight of milled material to produce a milled material composition. Useful binders include but are not limited to polyvinyl alcohol, polyvinyl butyral, aqueous acrylic polymer emulsions such as Rhoplex from Rohm & Haas, polyethyleneimine and mixtures thereof. The milled material composition is compressed at about 3000 PSI to about 10000 PSI, preferably about 5000 PSI to about 8000 PSI, more preferably about 5000 PSI to about 6000 PSI to yield a preform.

The preform is heated to about 500° C. to about 650° C., preferably about 550° C. to remove binder that may be present to yield a green preform. The green preform then is sintered at about 1000° C. to about 1250° C., preferably about 1050° C. to about 1150° C., more preferably about 1100° C. about 0.5 hr to about 5 hrs, preferably about 1 hr to about 2 hrs, more preferably about 2 hrs to yield a sintered product.

The sintered products are polished and electroded with fire-on-silver paste such a DuPont 6160 to produce an electroded sample. The electroded samples are poled at room temperature with an electric field of about 30 kV/cm to about 60 kV/cm, preferably about 40 kV/cm to about 50 kV/cm, more preferably about 40 kV/cm for about 3 min to about 30 min, preferably about 5 min to about 10 min, more preferably about 10 min.

The invention is further described below by reference to the following, non-limiting examples.

Example 1A

Manufacture of an Undoped Piezoelectric Compound of the Formula $x\text{Na}_{0.5}\text{Bi}_{0.5}\text{TiO}_3-y\text{K}_{0.5}\text{Bi}_{0.5}\text{TiO}_3-p\text{BaTiO}_3$ where x is 0.79, y is 0.14, and p is 0.07, Hereinafter Referred to as BNBK79

0.64 gms K_2CO_3 , 2.77 gms Na_2CO_3 , 10.57 gms TiO_2 , 14.19 gms Bi_2O_3 and 1.83 gms BaCO_3 are blended to yield a mixture. The mixture is calcined in air at 880° C. for 2 hrs to yield a calcined composition. The calcined composition then is vibration milled in anhydrous ethanol to produce a milled material that has a particle size of 1 micron. The milled material then is mixed with 2 wt. % Rhoplex binder from Rohm and Haas where the amount of binder is based on the weight of milled material. The resulting milled material-binder composition is compressed at 5000 PSI to yield a preform in the form of a disk that measures 12 mm diameter by 1 mm thick.

The preform is heated in air to 550° C. to burn out the binder and to yield a green preform. The green preform then is sintered in air at 1100° C. for 2 hrs to yield $x\text{Na}_{0.5}\text{Bi}_{0.5}\text{TiO}_3-y\text{K}_{0.5}\text{Bi}_{0.5}\text{TiO}_3-z\text{BaTiO}_3$ ($\text{B}_1\text{NB}_2\text{K}$) where x is 0.79, y is 0.14, and z is 0.07 sintered product. The sintered product is polished to 0.5 mm thickness and electroded with fire-on-silver paste (DuPont 6160) on the parallel faces for planar and thickness modes property characterizations.

terizations. The electroded disks are poled at 30° C. with an applied field of 60 kV/cm for 5 min.

Example 1B

Manufacture of Piezoelectric Compound that has the Formula $((x\text{Na}_{0.5}\text{Bi}_{0.5}\text{TiO}_3-y\text{K}_{0.5}\text{Bi}_{0.5}\text{TiO}_3-p\text{BaTiO}_3)-0.5\text{Mn})$ where x is 0.79, y is 0.14, and p is 0.07, Hereinafter Referred to as BNBK 79-0.5 wt % MnO_2

0.64 gms K_2CO_3 , 2.77 gms Na_2CO_3 , 10.57 gms TiO_2 and 14.19 gms Bi_2O_3 and 1.83 gms BaCO_3 are blended to yield a mixture. The mixture then is calcined in air at 880° C. for 2 hours to yield a calcined composition. The calcined composition then is mixed with 0.14 gms MnO_2 (0.5 wt % MnO_2 based on the weight of the calcined composition) to yield a doped mixture. The doped mixture is vibration milled in anhydrous ethanol to produce a milled material that has a particle size of 1 micron. The milled material is mixed with 2 wt. % Rhoplex binder from Rohm and Haas where the amount of binder is based on the weight of milled material. The resulting milled material-binder composition is compressed at 5000 PSI to yield a preform in the form of a disk that measures 12 mm diameter by 1 mm thick. The preform is heated in air to 550° C. to burn out the binder and to yield a green preform. The green preform then is sintered in air at 1100° C. for 2 hrs to yield a sintered piezoelectric compound of the formula $(x\text{Na}_{0.5}\text{Bi}_{0.5}\text{TiO}_3-y\text{K}_{0.5}\text{Bi}_{0.5}\text{TiO}_3-z\text{BaTiO}_3)-0.5\text{Mn}$ where x is 0.79, y is 0.14, and z is 0.07. The sintered product is polished to 0.5 mm thickness and electroded with fire-on-silver paste (DuPont 6160) on the parallel faces for planar mode property characterizations. The electroded disks are poled at 30° C. with an applied field of 60 kV/cm for 30 min.

Example 1C

Manufacture of Piezoelectric of the Formula $(x\text{Na}_{0.5}\text{Bi}_{0.5}\text{TiO}_3-y\text{K}_{0.5}\text{Bi}_{0.5}\text{TiO}_3-p\text{BaTiO}_3)-0.7\text{Mn}$ where x is 0.79, y is 0.14, and p is 0.07 Hereinafter Referred to as BNBK 79-0.7 wt % MnO_2

45 The procedure of example 1B is followed except that 0.2 gms. MnO_2 is employed.

Example 1D

Manufacture of Piezoelectric of the Formula $(x\text{Na}_{0.5}\text{Bi}_{0.5}\text{TiO}_3-y\text{K}_{0.5}\text{Bi}_{0.5}\text{TiO}_3-p\text{BaTiO}_3)-0.8\text{Mn}$ where x is 0.79, y is 0.14, and p is 0.07, Hereinafter Referred to as BNBK 79-0.8 wt % MnO_2

55 The procedure of example 1B is followed except that 0.23 gm of MnO_2 is employed.

Example 1E

Manufacture of Piezoelectric of the Formula $(x\text{Na}_{0.5}\text{Bi}_{0.5}\text{TiO}_3-y\text{K}_{0.5}\text{Bi}_{0.5}\text{TiO}_3-p\text{BaTiO}_3)-1.0\text{ wt.}$ % Mn where x is 0.79, y is 0.14, and p is 0.07 Doped with 1.0 wt % MnO_2 , Hereinafter Referred to as BNBK 79-1.0 wt % MnO_2

65 The procedure of example 1B is followed except that 0.28 gms. MnO_2 is employed.

11

Example 1F

Manufacture of Piezoelectric of the Formula
 $(xNa_{0.5}Bi_{0.5}TiO_3-yK_{0.5}Bi_{0.5}TiO_3-pBaTiO_3)-1.0$ wt
% CO_2O_3 where x is 0.79, y is 0.14, and p is 0.07
Doped with 1.0 wt % CO_2O_3 , Hereinafter Referred
to as BNBK 79-1.0 wt % CO_2O_3

The procedure of example 1B is followed except that 0.28
gms. CO_2O_3 is used as a dopant instead of MnO_2 .

Example 1G

Manufacture of Piezoelectric of the Formula
 $(xNa_{0.5}Bi_{0.495}TiO_3-yK_{0.5}Bi_{0.495}TiO_3-pBaTiO_3)-$
0.8Mn where x is 0.79, y is 0.14, p is 0.07, Herein-
after Referred to as Vacancy Defect Engineered
BNBK 79-0.8 wt % MnO_2

The procedure of example 1B is followed except that
14.05 gms Bi_2O_3 and 0.23 gms MnO_2 are employed.

Example 2

Manufacture of Piezoelectric of the Formula
 $xNa_{0.5}Bi_{0.5}TiO_3-yK_{0.5}Bi_{0.5}TiO_3-zLi_{0.5}Bi_{0.5}TiO_3$
where x=0.69, y=0.26 and z=0.05 Hereinafter
Referred to as ("BNBKT")

The procedure of example 1A is followed except that 1.35
gms K_2CO_3 , 2.74 gms Na_2CO_3 , 0.14 gms Li_2CO_3 , 14.40
gms TiO_2 and 17.30 gms Bi_2O_3 are employed.

Example 2A

Manufacture of Doped $(xNa_{0.5}Bi_{0.5}TiO_3-$
 $yK_{0.5}Bi_{0.5}TiO_3-zLi_{0.5}Bi_{0.5}TiO_3)-vMnO_2$ where
x=0.69, y=0.26 z=0.05 and v=0.8 wt %, Hereinaf-
ter Referred to as ("BNBKTR")

The procedure of example 1B is followed except that 1.35
gms K_2CO_3 , 2.74 gms Na_2CO_3 , 0.14 gms Li_2CO_3 , 14.40
gms TiO_2 and 17.30 gms Bi_2O_3 and 0.27 gm MnO_2 are
employed.

Example 3

Manufacture of $xNa_{0.5}Bi_{0.5}TiO_3-zBaTiO_3$ ($x+z=1$)
where x=0.8 and z=0.2

The procedure of example 1A is followed except that 3.26
gms Na_2CO_3 , 12.31 gms TiO_2 , 14.34 gms Bi_2O_3 and 6.06
gms $BaCO_3$ are used as starting materials.

Example 4

Manufacture of $xNa_{0.5}Bi_{0.5}TiO_3-yK_{0.5}Bi_{0.5}TiO_3$
($x+y=1$) where x=0.7 and (y=0.3)

The procedure of example 1A is followed except that 1.59
gms K_2CO_3 , 2.85 gms Na_2CO_3 , 12.31 gms TiO_2 , 17.92 gms
 Bi_2O_3 are employed as starting materials.

12

Example 5

Manufacture of $xNa_{0.5}Bi_{0.5}TiO_3-yK_{0.5}Bi_{0.5}$
 $TiO_3-zLi_{0.5}Bi_{0.5}TiO_3-pBaTiO_3$ ($x+y+z+p=1$)
5 ("BNKLBT"), where x=0.83, y=0.084, z=0.03 and
p=0.056

The procedure of example 1A is followed except that
0.445 gms K_2CO_3 , 3.38 gms Na_2CO_3 , 0.085 gms Li_2CO_3 ,
10 1.70 gms $BaCO_3$, 12.31 gms TiO_2 and 16.92 gms Bi_2O_3 are
employed as starting materials.

Example 5A

15 Manufacture of $(xNa_{0.5}Bi_{0.5}TiO_3-yK_{0.5}Bi_{0.5}TiO_3-$
 $zLi_{0.5}Bi_{0.5}TiO_3-pBaTiO_3)-rCO_2O_3$ where x=0.83,
y=0.084, z=0.03, p=0.056 and r=1.5 wt %

20 The procedure of example 1B is followed except that
0.445 gms K_2CO_3 , 3.38 gms Na_2CO_3 , 0.085 gms Li_2CO_3 ,
1.70 gms $BaCO_3$, 12.31 gms TiO_2 , 16.92 gms Bi_2O_3 and
0.49 gms CO_2O_3 are employed as starting materials.

Example 6

25 Manufacture of Vacancy Defect Engineered
 $(xNa_{0.5}Bi_{0.495}TiO_3-yK_{0.5}Bi_{0.495}$
 $TiO_3-zLi_{0.5}Bi_{0.495}TiO_3-pBaTiO_3)-rCO_2O_3$, where
x=0.83, y=0.084, z=0.03, p=0.056 and r=1.5 wt %

30 The procedure of example 1B is followed except that
0.445 gms K_2CO_3 , 3.38 gms Na_2CO_3 , 0.085 gms Li_2CO_3 ,
1.70 gms $BaCO_3$, 12.31 gms TiO_2 , 16.75 gms Bi_2O_3 and
0.49 gms CO_2O_3 are employed as starting materials.

Example 7

35 $xNa_{0.5}Bi_{0.5}TiO_3-yK_{0.5}Bi_{0.5}TiO_3-zLi_{0.5}Bi_{0.5}TiO_3-$
 $pBaTiO_3$ ($x+y+z+p=1$) ("BNKLBT"), where
x=0.85, y=0.072, z=0.03 and p=0.048

The procedure of example 1A is followed except that 0.38
gms K_2CO_3 , 3.47 gms Na_2CO_3 , 0.085 gms Li_2CO_3 , 1.45
gms $BaCO_3$, 12.31 gms TiO_2 , and 17.06 gms Bi_2O_3 are
employed as starting materials.

Example 8

40 $xNa_{0.5}Bi_{0.5}TiO_3-yK_{0.5}Bi_{0.5}TiO_3-zLi_{0.5}Bi_{0.5}TiO_3-$
 $pBaTiO_3$ ($x+y+z+p=1$) ("BNKLBT"), where
x=0.80, y=0.102, z=0.03 and p=0.068

45 The procedure of example 1A is followed except that 0.54
gms K_2CO_3 , 3.26 gms Na_2CO_3 , 0.085 gms Li_2CO_3 , 2.06
gms $BaCO_3$, 12.31 gms TiO_2 , and 16.70 gms Bi_2O_3 are
employed as starting materials.

Example 9

50 $(xNa_{0.5}Bi_{0.5}TiO_3-yK_{0.5}Bi_{0.5}TiO_3-zLi_{0.5}Bi_{0.5}TiO_3-$
 $pBaTiO_3)-rCO_2O_3$, r=1.5%, ($x+y+z+p=1$) where
x=0.85, y=0.072, z=0.03 and p=0.048

55 The procedure of example 1B is followed except that 0.38
gms K_2CO_3 , 3.47 gms Na_2CO_3 , 0.085 gms Li_2CO_3 , 1.45
gms $BaCO_3$, 12.31 gms TiO_2 , 17.06 gms Bi_2O_3 and 0.49
gms CO_2O_3 are employed as starting materials.

US RE46,445 E

13

Example 10

The procedure of example 1B is followed except that 0.54 gms K_2CO_3 , 3.26 gms Na_2CO_3 , 0.085Li₂CO₃, 2.06 gms

14

$BaCO_3$, 12.31 gms TiO_2 , 16.70 gms Bi_2O_3 and 0.49 gms CO_2O_3 are employed as starting materials.

Various properties of BNBK type ceramics as compared to commercial PZT ceramics is shown in Tables II, III and IV. The polarization hysteresis for BNBK 79-0.8 wt % MnO_2 piezoelectric compound of example 1G compared to PZT4 and PZT8 is shown in FIG. 3;

TABLE II

Characteristic piezoelectric properties of BNBK lead free ceramics compared to commercial hard PZT.

FIG. 3 shows polarization hysteresis for BNBK 79-0.8 wt % MnO_2 piezoelectric compound of example 1G compared to PZT4 and PZT8;

FIG. 4 shows strain hysteresis of lead free BNBK 79 of example 1A and 0.8 wt % MnO_2 doped BNBK 79 of example 1G piezoelectric compounds compared to PZT4 and PZT8;

FIG. 5 (a) shows temperature dependence of dielectric behavior for undoped BNBK 79 of example 1A. FIGS. 5(b)-(d) show temperature dependence of dielectric behavior for Mn doped BNBK79 piezoelectric compounds of examples 1B, 1D and 1E respectively. As shown in FIGS. 5(a)-5(d), depolarization temperature (T_d) decreases slightly from 250° C. to 230° C. with increasing Mn dopant level.

FIG. 6 shows temperature dependence of electromechanical coupling factors (k_{ij}) for vacancy defect engineered 0.8 wt. % MnO_2 doped BNBK79 piezoelectric compound of example 1G. Lateral coupling factor k_{31} is 7% at room temperature and thickness coupling factor k_t is 44% at room temperature. As shown in FIG. 6, k_{31} increases to 10% at 235° C. and k_t increases to 50% at 235° C.

FIG. 7 shows planar electromechanical coupling factor variation as a function of temperature for vacancy defect engineered BNBK79-0.8 wt % MnO_2 piezoelectric compound of Example 1G compared to PZT 4 and PZT8. As shown in FIG. 7, planar electromechanical coupling factor increases slightly with temperature up to 235° C., whereas

exhibiting a very stable temperature behavior till their depolarization temperature T_d .

FIG. 10 shows the temperature dependence of mechanical quality factor Q, for Co_2O_3 doped vacancy defect engineered BNKLBT ceramics of examples 10, 5A and 9, where the Q values are larger than 700 at room temperature, gradually decreased with increasing temperature, keep yet high Q value around 200 when the temperature approaching the depolarization temperature T_d .

The disclosed piezoelectric compounds may be employed in electronic devices such as ultrasonic transducers that typically operate at 20 kHz and above as well as in high intensity focused ultrasound (HIFU) transducers. The disclosed piezoelectric compounds also may be employed as stators in ultrasonic motors and as components in piezoelectric transformers.

Ultrasonic motors, and their construction, are well known as shown in U.S. Pat. No. 7,576,472, the teachings of which are incorporated by reference herein by their entirety. Piezoelectric transformers and their construction also are known, as shown by U.S. Pat. No. 7,593,241, the teachings of which are incorporated by reference herein by their entirety.

The invention claimed is:

1. A piezoelectric compound having [the] formula $x\text{Na}_m\text{Bi}_n\text{TiO}_3-y\text{K}_m\text{Bi}_n\text{TiO}_3-z\text{Li}_m\text{Bi}_n\text{TiO}_3-p\text{BaTiO}_3$ where

$[0 < x \leq 1], [0 \leq y \leq 1], [0 \leq z \leq 1], [0 < p < 1], [0 < x \leq 0.85], (0 < y < 1)$
 $(0 < z < 1), (0 < p < 1), (x+y+z+p=1), (0.3 \leq m \leq 0.7), (0.3 \leq n \leq 0.7)$, and $(0.9 \leq m/n \leq 1.1)$.

2. A piezoelectric compound having [the] formula $(xNa_mBi_nTiO_3-yK_mBi_nTiO_3-zLi_mBi_nTiO_3-pBaTiO_3)-rM$ where $[0 < x \leq 1], [0 \leq y \leq 1], [0 < z \leq 1], [0 < p < 1], [0 < x \leq 0.85], (0 < y < 1), (0 < z < 1), (0 < p < 1), (x+y+z+p=1), (0.3 \leq m \leq 0.7), (0.3 \leq n \leq 0.7), (0.9 \leq m/n \leq 1.1)$ and $(0 \text{ wt \%} < r \leq 5 \text{ wt \%})$ where r is based on the weight of a compound within [the scope of] formula $xNa_mBi_nTiO_3-yK_mBi_nTiO_3-zLi_mBi_nTiO_3-pBaTiO_3$ and M is a dopant selected from the group consisting of Al_2O_3 , CoO , Re_2O_3 where Re is a rare earth element, NiO , MnO_2 , Fe_2O_3 , and mixtures thereof.

3. A piezoelectric compound having [the] formula

where $[0 < x \leq 1], [0 \leq y \leq 1], [0 < z \leq 1], [0 < x < 1], (0.2 \leq y < 1), (0 < z < 1), (x+y+z=1), (0.3 \leq m \leq 0.7), (0.3 \leq n \leq 0.7), (0.9 \leq m/n < 1.1)$ and $(0.9 \leq m/n \leq 1.1)$.

4. A piezoelectric compound having [the] formula $(xNa_mBi_nTiO_3-yLi_mBi_nTiO_3-zBaTiO_3)-wN$ where $[0 < x \leq 1], [0 \leq y \leq 1], [0 < z \leq 1], [0 < x < 1], (0 < y < 1), (0 < z < 1), (x+y+z=1), (0.3 \leq m \leq 0.7), (0.3 \leq n \leq 0.7), (0.9 \leq m+n < 1.1), (0.9 \leq m/n < 1.1)$ and $(0 < w \leq 5 \text{ wt \%})$ where w is based on the weight of a compound within [the scope of] the formula $xNa_mBi_nTiO_3-yLi_mBi_nTiO_3-zBaTiO_3$ and where N is a dopant selected from the group consisting of Al_2O_3 , CoO , Re_2O_3 where Re is a rare earth element, NiO , MnO_2 , Fe_2O_3 , and mixtures thereof.

5. A piezoelectric compound having [the] formula $(xNa_mBi_nTiO_3-yK_mBi_nTiO_3-zLi_mBi_nTiO_3-pBaTiO_3)-rM$ where $[0 < x \leq 1], [0 \leq y \leq 1], [0 < p < 1], [0 < x < 1], (0 < y < 1), (0 < p < 1), (0 < z \leq 0.2), (x+y+z+p=1), (0.3 \leq m \leq 0.7), (0.3 \leq n \leq 0.7), (0.9 \leq m/n \leq 1.1)$ and $(0 \text{ wt \%} < r \leq 5 \text{ wt \%})$ where r is based on the weight of a compound within [the scope of] formula $xNa_mBi_nTiO_3-yK_mBi_nTiO_3-zLi_mBi_nTiO_3-pBaTiO_3$ and M is a dopant selected from the group consisting of Al_2O_3 , CoO , Re_2O_3 where Re is a rare earth element, NiO , MnO_2 , Fe_2O_3 , and mixtures thereof.

6. The compound of claim 5 wherein $m=0.5$ and $n=0.495$.

7. The compound of claim 2 wherein a source of M is Co_2O_3 , x is 0.80, y is 0.102, z is 0.03, p is 0.068 and r is 1.5%.

8. The compound of claim 7 wherein $m=0.5$ and $n=0.495$.

9. A piezoelectric compound having [the] formula $xNa_{0.5}Bi_{0.5}TiO_3-yLi_{0.5}Bi_{0.5}TiO_3-zBaTiO_3$ where $(0.3 \leq x \leq 0.95), [0 < y \leq 0.7], (0.2 \leq y \leq 0.7), (0 < z \leq 0.2)$ and $(x+y+z=1)$.

10. A method of manufacture of a piezoelectric compound of [the] formula $xNa_{0.5}Bi_{0.5}TiO_3-yK_{0.5}Bi_{0.5}TiO_3-zBaTiO_3$ where $[0 < x \leq 1], [0 < y \leq 1], [0 < z \leq 1], [0 < x < 1], (0.7 < y < 1), (0 < z < 1)$, and $(x+y+z=1)$ comprising, forming a mixture of K_2CO_3 , Na_2CO_3 , $BaCO_3$, Bi_2O_3 [or] and TiO_2 starting materials in amounts suitable for yielding a compound within formula $xNa_{0.5}Bi_{0.5}TiO_3-yK_{0.5}Bi_{0.5}TiO_3-zBaTiO_3$, calcining the mixture at about $800^\circ C$. to about $950^\circ C$. for about 0.5 hrs to about 2 hrs to yield a calcined mixture, milling the calcined mixture to a particle size of about 0.5 microns to about 2 microns to produce a [calcined] milled mixture, compressing the [calcined] milled mixture at about 3000 PSI to about 10000 PSI to yield a preform, heating the preform to a temperature of about $500^\circ C$. to about $600^\circ C$. to yield a green preform, sintering the green preform at about $1060^\circ C$. to about $1220^\circ C$. for about 0.5 hrs to about 2 hrs to yield a piezoelectric compound of the formula

$xNa_{0.5}Bi_{0.5}TiO_3-yK_{0.5}Bi_{0.5}TiO_3-zBaTiO_3$ where $[0 < x \leq 1], (0 < y \leq 1), (0 < z \leq 1), [0 < x < 1], (0.7 < y < 1), (0 < z < 1)$, and $(x+y+z=1)$.

11. A method of manufacture of a piezoelectric compound of [the] formula $(xNa_{0.5}Bi_{0.5}TiO_3-yK_{0.5}Bi_{0.5}TiO_3-zBaTiO_3)-rM$ where $[0 < x \leq 1], (0 < y \leq 1), (0 < z \leq 1), [0 < x < 1], (0 < y < 1), (0 < z < 1), (x+y+z=1), (0 < r \leq 5 \text{ wt \%})$ where r is based on the weight of a compound within formula $xNa_{0.5}Bi_{0.5}TiO_3-yK_{0.5}Bi_{0.5}TiO_3-zBaTiO_3$ and M is a dopant [comprising,] wherein the method comprises forming a mixture of K_2CO_3 , Na_2CO_3 , $BaCO_3$, Bi_2O_3 [or] and TiO_2 starting materials in amounts suitable for yielding a compound within [the] formula $xNa_{0.5}Bi_{0.5}TiO_3-yK_{0.5}Bi_{0.5}TiO_3-zBaTiO_3$ where $[0 < x \leq 1], (0 < y \leq 1), (0 < z \leq 1), [0 < x < 1], (0 < y < 1), (0 < z < 1), (x+y+z=1)$, calcining the mixture at about $800^\circ C$. to about $950^\circ C$. for about 0.5 hrs to about 2 hrs to yield a calcined mixture, blending a source of dopant M wherein the source is selected from the group consisting of Al_2O_3 , CoO , $[Co_2O_3]$, Re_2O_3 where Re is a rare earth element, $NiCO_3$, MnO_2 , $MnCO_3$, Fe_2O_3 , and mixtures thereof with the calcined mixture to produce a doped mixture,

25 milling the doped mixture to a particle size of about 0.5 microns to about 2 microns to produce a [calcined] milled mixture, compressing the [calcined] milled mixture at about 3000 PSI to about 10000 PSI to yield a preform, heating the preform to a temperature of about $500^\circ C$. to about $600^\circ C$. to yield a green preform, and sintering the green preform at about $1060^\circ C$. to about $1220^\circ C$. for about 0.5 hrs to about 2 hrs to yield a piezoelectric compound of [the] formula $(xNa_{0.5}Bi_{0.5}TiO_3-yK_{0.5}Bi_{0.5}TiO_3-zBaTiO_3)-rM$ where $[0 < x \leq 1], (0 < y \leq 1), (0 < z \leq 1), [0 < x < 1], (0 < y < 1), (0 < z < 1), (x+y+z=1), (0 < r \leq 5 \text{ wt \%})$.

35 12. An ultrasonic transducer comprising the piezoelectric of claim 2.

13. The transducer of claim 12 wherein the transducer is a high intensity focused ultrasound (HIFU) transducer.

40 14. An ultrasonic motor comprising a piezoelectric compound of claim 2.

15. A piezoelectric transformer comprising a piezoelectric compound of claim 2.

45 16. A piezoelectric compound according to claim 1 wherein $(0 < x \leq 0.85), (0 < y < 1), (0 < z < 0.2), (0 < p < 0.1), (x+y+z+p=1), (0.3 \leq m \leq 0.7), (0.3 \leq n \leq 0.7)$, and $(0.9 \leq m/n \leq 1.1)$.

50 17. A Co-doped $xNa_mBi_nTiO_3-yK_mBi_nTiO_3-zLi_mBi_nTiO_3-pBaTiO_3$ piezoelectric compound where $(0 < x \leq 1), (0 < y < 1), (0 < z < 1), (0 < p < 1), (x+y+z+p=1), (0.3 \leq m \leq 0.7), (0.3 \leq n \leq 0.7), (0.9 \leq m/n \leq 1.1)$, wherein Co_2O_3 is a source of Co dopant.

18. A Co-doped piezoelectric compound according to claim 17 where the Co dopant is present in an amount of 1.5 wt % based on the weight of $xNa_mBi_nTiO_3-yK_mBi_nTiO_3-zLi_mBi_nTiO_3-pBaTiO_3$ piezoelectric compound.

55 19. A Co-doped piezoelectric compound according to claim 18 where $0.80 \leq x \leq 0.85$, $0.072 \leq y \leq 0.102$, $z=0.03$, and $0.048 \leq p \leq 0.068$.

20. The compound of claim 19 where x is 0.80, y is 0.102, z is 0.03, and p is 0.068.

60 21. Process for manufacture of Co doped $xNa_{0.5}Bi_{0.5}TiO_3-yK_{0.5}Bi_{0.5}TiO_3-zLi_{0.5}Bi_{0.5}TiO_3-pBaTiO_3$ piezoelectric compound where $0.80 \leq x \leq 0.85$, $0.072 \leq y \leq 0.102$, $z=0.03$, and $0.048 \leq p \leq 0.068$ comprising, forming a mixture of K_2CO_3 , Na_2CO_3 , Li_2CO_3 , $BaCO_3$, TiO_2 and Bi_2O_3 , calcining the mixture to form a calcined composition, mixing the calcined composition with Co_2O_3 to form a doped composition, and sintering the doped composi-

tion to form Co doped $xNa_{0.5}Bi_{0.5}TiO_3-yK_{0.5}Bi_{0.5}TiO_3-zLi_{0.5}Bi_{0.5}TiO_3-pBaTiO_3$ where $0.80 \leq x \leq 0.85$, $0.072 \leq y \leq 0.102$, z is 0.03 , $0.048 \leq p \leq 0.068$ and $(x+y+z+p=1)$.

22. The process of claim 21 wherein the mixture comprises 1.09 wt. % - 1.54 wt. % K_2CO_3 , 9.32 wt. % - 9.98 wt. % Na_2CO_3 , 0.243 wt. % - 0.244 wt. % Li_2CO_3 , 4.17 wt. % - 5.89 wt. % $BaCO_3$, 35.22 wt. % - 35.42 wt. % TiO_2 , and 47.77-49.09 wt. % Bi_2O_3 , where all amounts are based on total weight of the mixture, and wherein the calcining is performed at $880^\circ C$.

23. The process of claim 22 wherein the sintering is performed at $1100^\circ C$.

24. The process of claim 23 wherein the sintering is performed for 2 hrs.

25. The product of the process of claim 24.

26. The compound of claim 1 wherein $(0.2 \leq y < 1)$.

27. The compound of claim 4 wherein $(0.2 \leq y < 1)$.
